(57) **CLAIM**

The ornamental design for a syringe luer lock with stabilizer, as shown & described.

DESCRIPTION

FIG. 1 is a perspective exploded view of a syringe luer lock with stabilizer showing my new design;

FIG. 2 is a left side elevation view thereof;

FIG. 3 is a top elevation view thereof;

FIG. 4 is a right side elevation view thereof;

FIG. 5 is bottom elevation view thereof;

FIG. 6 is a front elevation view thereof;

FIG. 7 is a rear elevation view thereof;

FIG. 8 is a top elevation view of a syringe luer lock with stabilizer in a assembled configuration; and,

FIG. 9 is a left side elevation view thereof.

The features shown in broken lines depict environmental subject matter only and form no part of the claimed design.
